Patented Mar. 2, 1920.

UNITED STATES PATENT OFFICE.

JEANNETTE N. JOHNSON, OF OMAHA, NEBRASKA.

COMBINED PASTEBORD BASSINET AND DOLL.

1,332,400.

Specification of Letters Patent.

Patented Mar. 2, 1920.

Application filed October 28, 1919. Serial No. 334,044.

To all whom it may concern:

Be it known that I, JEANNETTE N. JOHNSON, a citizen of the United States, residing at Omaha, in the county of Douglas, State 5 of Nebraska, have invented certain new and useful Improvements in Combined Pasteboard Bassinets and Dolls, of which the following is a description, reference being had to the accompanying drawing and to the 10 figures of reference marked thereon.

The invention relates to new and useful improvements in a combined pasteboard bassinet and doll, and more particularly to a bassinet having a hood at one end thereof.

15 An object of the invention is to provide as an article of manufacture a cardboard cut to shape and decorated to represent a covered bassinet, which cardboard is cut through in a continuous line along the upper edge of the robe in the bassinet, a portion 20 of the upper edge of the bassinet and a portion of the front edge of the hood or cover so that a cardboard doll may be inserted in said slot formed by the cutting of 25 the cardboard bassinet, whereby a portion of the body of the doll is concealed by the robe and the front wall of the bassinet and a portion of the head of the doll is concealed by the hood or cover, thus giving the 30 appearance of a doll within the bassinet, said line of cutting being wholly within the limits of the cardboard bassinet whereby the spring of the cardboard will clamp and hold the doll in place.

35 In the drawings:—

Figure 1 is a front view of a cardboard bassinet and doll embodying my improvements;

Fig. 2 is a front view of a portion of the 40 upper part of the bassinet showing the doll as supported in an upright position therein; and

Fig. 3 is a vertical sectional view on the line 3—3 of Fig. 1.

45 In carrying out the invention, a piece of comparatively stiff cardboard is cut to shape and decorated to represent a bassinet having a hood or cover at one end thereof. The bassinet is provided with the basket 50 portion 1 having wheels 2—2 and a hood or cover 3. Within the bassinet is a robe 4. Said bassinet is provided with decorations 55 indicating a woven-in ribbon passing through the bassinet. The hood is also provided with suitable ribbon decorations, indicated at 6.

The cardboard is cut along the line *a*—*a*, which is the upper line of the robe within the bassinet. It is noted that this line curves upwardly, as indicated at *b*, thus 60 forming a shoulder in the line. The upper edge of the bassinet is cut along the line *a* to *c*, while the hood or cover is cut along the line from *c* to *d*. This line *a* to *c* and *c* to *d* is a continuous line, and said line 65 lies wholly within the limits of the cardboard forming the bassinet. Said line of cutting extends from the point *c* toward the front of the hood or cover and toward the front of the bassinet, thus forming a tongue 70 portion which may be sprung backwardly to receive the cardboard doll, and the spring of the cardboard will cause said projecting portion to clamp and hold the doll, as will be hereinafter more fully disclosed. 75

The cardboard doll consists in a body portion 7 having legs 8, which are indicated as in a drawn-up position, arms 9, and a head 10. The cardboard doll is adapted to be inserted in the slot formed by the cutting 80 of the cardboard forming the bassinet with the body portion, or the greater portion thereof, hidden by the robe in the front wall of the bassinet, as clearly shown in Fig. 1 of the drawings. A portion of the head is 85 also hidden by the front part of the hood or cover so that, when the doll is in place, it will be firmly clamped between the cut portions of the cardboard forming the bassinet and will have the appearance of a doll being 90 within the bassinet. At the same time, the doll may be removed from the bassinet and placed as indicated in Fig. 2, with the arms of the doll resting on the upper edge of the slot between *a* and *b* and in front of the 95 shoulder at *b* and with the body portion bearing against the edge of the hood along the line *c*—*d* and adjacent the point *c*. This, together with the spring of the cardboard clamping the cardboard doll will hold the 100 doll firmly in this upright position.

From the above description, it will be apparent that I have provided a combined cardboard bassinet and doll wherein the doll may be placed relative to the cut parts of the 105 bassinet so as to have the appearance of being within the bassinet, or may be placed in sitting position in the bassinet and firmly held in such position.

It is understood, of course, that the usual 110 removable dresses having tabs for holding the same on the body portion of the doll may

be provided. At the back of the cardboard forming the bassinet is a pocket 11 which is formed by a sheet of paper 12 cemented at 13 and along its side edges to the cardboard, 5 leaving the upper edge thereof free. As shown in Fig. 3 of the drawings, the body portion of the doll which is in rear of the robe and the side wall of the bassinet is within this pocket. This pocket may also 10 be used to store the different dresses which are to be used in connection with the cardboard doll.

It is obvious that minor changes in the shaping of the parts and the line of cutting 15 of the cardboard of the bassinet may be made without departing from the spirit of the invention as set forth in the appended claim.

Having thus described my invention, what 20 I claim as new and desire to secure by Letters-Patent is:—

As an article of manufacture, a combined cardboard bassinet and doll comprising, a

cardboard cut to shape and decorated to represent a hood covered bassinet and a robe 25 in the bassinet, said cardboard being cut through in a continuous line along the upper edge of the robe in the bassinet, a portion of the upper edge of the bassinet and a portion of the front edge of the hood, and 30 adapted to receive in the slot formed by the cutting of said cardboard a cardboard doll shaped so that a portion of the body thereof is hidden by the robe and the front wall of the bassinet and a portion of the head may 35 be hidden by the hood, thereby giving the appearance of a doll within the bassinet, said line of cutting lying wholly within the limits of the cardboard forming the bassinet so that the cardboard doll will be clamped 40 and held in place by the spring of the cardboard forming the bassinet.

In testimony whereof, I affix my signature.

JEANNETTE N. JOHNSON.
